NECKBAND LOOP

William A. Keys, New York, N. Y.

Application August 20, 1938, Serial No. 225,879

1 Claim. (Cl. 24—50)

This invention relates to neckties, and more particularly to a loop member utilized as a part of the means by which the neckbands of certain types of bow ties are made adjustable to fit different sized collars.

At the present time, neckties of this character utilize a metal loop member as a part of the adjusting means, examples of which will be found in my Patents Nos. 2,020,507 and 1,962,600. It has been found that under comparatively rough treatment and extraordinary pulling strain imposed on the opposite ends of the neckties, the loop member will often assume an angular position, the opposite ends of the neckband of the tie sliding in the loop to the narrower ends thereof and becoming wrinkled and bunched and the tie elongated by reason of the angularity of the loop member.

The main object of the present invention is to provide a loop member for use in adjustable neckbands, in which the tendency of the loop member to become angularly disposed is prevented and in which also, any tendency of the ends of the neckband to slide toward the smaller ends of the loop member will be completely obviated so that the band will remain flat and unwrinkled and retain its position of adjustment indefinitely.

In the accompanying drawing, in which an embodiment of the invention is shown, Fig. 1 is a face view of the improved loop member; Fig. 2 is a sectional view on the line 2—2 of Fig. 3, looking in the direction of the arrows; Fig. 3 is a face view of a portion of a neckband showing the improved loop member in position; and Fig. 4 is an edge view of the structure of Fig. 5.

The improved loop member 5 consists of an elongated element in the form of a plate preferably formed from a single piece of sheet metal. It is provided with the elongated slot 7 through which the ends 1 and 3 of the neckband extend in the conventional manner, the loop portion 3 of the neckband extending around the side or leg 6 of the loop member 5, while the neckband-end 1 extends over and encloses the wider, flat, plate-like portion 8 formed as an integral portion of member 5. The folded-over end 2 of the neckband portion 1 is stitched to the plate 8 by means of stitches 11 which extend across the neck-band and pass through holes or perforations 9 formed in plate 8, the stitching so employed being preferably concealed or indiscernible from the out-

side of the neckband. The folded-over portion 2 of the neckband is stitched down by means of the line of stitching 10, which can also, if desired, be of a concealed nature and not visible on the outside of the neckband.

With the structure described, it will be apparent that since the plate portion 8 of the loop member 5 is stitched down on the end portion 1 for the width of the neckband, the neckband portion 1 cannot move up or down in the slot 10 and longitudinally of the loop member. Consequently, the loop member cannot possibly assume an angular position, but remains indefinitely as shown in Fig. 3, holding the band flat and unwrinkled and co-operating in the maintenance of 15 the band in any desired position of adjustment.

If desired, the plate portion 8 of the loop may have the holes 9 omitted. In such case a line of stitching as indicated at 15 in Fig. 3 located relatively close to the angular edge of the plate 20 portion 8 will hold the loop in position and serve to prevent crumpling or gathering of the part 1 of the neck-tie within the loop. The line of stitching indicated at 15 may be in such case used as a substitute also for the stitches 10, so 25 that one line of stitching extending across the neck-band portion 11 will serve to hold down the over-turned portion 2 and secure the loop in position.

While I have shown one embodiment of the 30 invention, it will be obvious that the invention is not to be restricted thereto, but is broad enough to cover all structures coming within the scope of the annexed claim.

What I claim is:

In a necktie construction, a necktie band portion having two ends, a loop member connecting said ends, said loop member comprising a plate formed with an elongated slot through which two ends of the neckband pass, said plate being formed 40 of a continuous single piece of sheet metal and having a wide, flat tab portion provided with inclined edges disposed at one side of the slot, all portions of the plate being in the same plane, and stitching in that end of the neckband which 45 overlies the tab portion of the plate, said stitching being so disposed in relation to the tab portion of the plate to thereby hold said tab portion so that movement of the loop or tab portion thereof transversely of the neckband is prevented. 50

WILLIAM A. KEYS.
